STEEL BOILER

Howard G. Smith, Chinchilla, Pa.

Application June 12, 1934, Serial No. 730,175

6 Claims. (Cl. 122—42)

My invention relates to a new and useful steel boiler, that is a boiler which can be fabricated in complete, relatively small, independent units, which are adapted to be easily and quickly assembled on location, thereby permitting the installation of relatively large boilers in buildings having small entrances, the boiler being taken into the building in preassembled sections and then assembled.

10 My invention still further relates to a steel boiler of this character, whereby I combine the advantages of a water tube and a fire tube boiler in one construction, thereby greatly increasing the efficiency and utility of the boiler.

15 My invention still further relates to a novel steel boiler of the character described, in which the fire and the heated products of combustion are so baffled as to insure the maximum of contact of the sources of heat with the water to be heated.

20 completely to utilize the heat values produced without unduly hampering combustion or interfering with the proper draft of the boiler.

My invention still further relates to a highly simplified form of boiler which, while including all of the foregoing advantages, is inexpensive to make and assemble.

In the accompanying drawings:

Fig. 1 represents a front elevation of a boiler embodying my invention.

90 Fig. 2 represents a section on line 2—2 of Fig. 1.
Fig. 3 represents a foreshortened diagrammatic and fragmentary vertical sectional view showing details of construction, certain parts being shown in elevation.

35 Fig. 4 represents a section on line 4-4 of Fig. 2.
Fig. 5 represents a section on line 5-5 of Fig. 3.

Fig. 6 represents a section on line 6—6 of Fig. 4. Referring to the drawings, in which like refer-

ence characters indicate like parts, my novel boiler consists generally of three units 1, 2 and 3, each of which is prefabricated and assembled independently of the others, all of said units being adapted for assembly with respect to each other and with respect to a conventional base or foundation 4. The unit 1 comprises a front water-head 6 and a rear water-head 7, said water-heads being interconnected by means of the relatively large inclined water tubes 9. The water tubes 9

as shown in Figs. 1, 4 and 5, are disposed in opposite vertical rows A and B, together with the two or more horizontal rows C, so as to surround the fire-box 10, access to which is had through the fire door 11. While the drawings shows the construction adapted for a coal burning boiler, it is obvious that it is equally well adapted to an oil

burning furnace without departure from the scope of the invention.

Each of the sections 2 and 3 is formed of a drum 12 which extends the entire length of the boiler from the front head 6 to the rear head 7, each of said drums being provided with the fire tubes 13 which open at their front end into the smoke header 14 and at their rear end into the stack 15. Each of the drums 12 communicates at its front and rear ends with the water-heads 6 and 7, as shown at 16 in Fig. 2, so that the water of the heads 6 and 7 circulates freely through the drums 12. 18 represents a baffle extending from the front head 6 inwardly to any desired extent within the boiler so as to deflect the fire rearwardly towards the rear head 7. The flames and heated products of combustion then rise upwardly between the drums 12 and enter the front smoke header 14, the flames and heated products of combustion being prevented from passing out directly through the stack 15 by the brick wall 19, or other baffle, which completely closes the smoke stack 15 from any communication with the fire chamber 10. From the front smoke header 14 the heated gases enter the fire tubes 13 in the direction of the arrows 20 in Fig. 6 and pass through the fire tubes 13 into the smoke stack 15. Deflection of the heated gases, first, rearwardly by the baffle 18, and then forwardly into the front smoke header 14 by the baffle 19, and the passage of the gases through the fire tubes 13 in the drums 12, insures complete exhaustion of the heat of the gases and the transfer of their heat to the water in the drums 12 prior to their escape through the smoke stack 15. The boiler may be provided with any suitable insulation 21 on the sides.

It will thus be seen that the water is first exposed to the direct flame in the fire box with the tubes 9 arranged as shown at A, B and C, in Fig. 5, as well as in the front and rear water-heads 6 and 7. This causes the water to circulate upwardly in the tubes 9 from the rear head 7 towards the front head 6, the flames being then directed upwardly against and between the two units or drums 12 and then through the fire tubes 13 which extend through the drums 12 and are surrounded by the water therein. 40 45

It will further be seen that by my novel arrangement I am enabled to fabricate the units 1, 2 and 3 separately and transport them separately to the point of use where the units 1, 2 and 3 are set up on the foundation 4 and assembled with respect to each other on location. 50

I claim:

1. A steel boiler, comprising an integral lower 55

- unit consisting of front and rear water-heads extending the entire width of the boiler, and inclined water tubes interconnecting said front and rear water-heads, a plurality of spaced upper 5 water drums welded on to and communicating with said front and rear water-heads at the upper ends thereof, a smoke header coinciding with the front of said upper water drums, a smoke stack coinciding with the rear ends of 10 said upper water drums, fire tubes extending through said water drums and communicating with said smoke header and said rear smoke stack, and means for preventing communication between the fire box and said rear smoke stack, 15 whereby the products of combustion are compelled to rise through said lower unit between and around said upper water drums into said front smoke header and through said fire tubes into said rear smoke stack.
- 20 2. A steel boiler, comprising an integral lower unit consisting of front and rear water-heads extending the entire width of the boiler, and inclined water tubes interconnecting said front and rear water-heads, said water tubes being 25 arranged along the sides and top of said lower unit, a plurality of spaced upper water drums welded on to and communicating with said front and rear water-heads at the upper ends thereof, a smoke header coinciding with the front of said 30 upper water drums, a smoke stack coinciding with the rear ends of said upper water drums, fire tubes extending through said water drums and communicating with said front smoke header and said rear smoke stack, means for preventing communication 35 between the fire box and said rear smoke stack, whereby the products of combustion are compelled to rise through said lower unit between and around said upper water drums into said front smoke header and through said fire tubes into said rear smoke stack, and a baffle 40 extending rearwardly from said front water-head intermediate said lower unit and said upper water drums.
- 45 3. A boiler comprising a lower unit adapted to be positioned on a prepared foundation and consisting of a front water-head extending the entire width of the boiler, a rear water-head extending the entire width of the boiler, and relatively large, inclined water tubes interconnecting said front and rear water-heads, and one or more upper 50 water drums welded on to said lower unit, each of said upper water drums having fire tubes passing therethrough and communicating with the combustion chamber of the boiler, and each of said drums being also connected at its front and rear ends with said front and rear water-heads,

said drums being also connected at its front and rear ends with said front and rear water-heads.

4. A boiler comprising a lower unit adapted to be positioned on a prepared foundation and consisting of a front water-head extending the entire width of the boiler, a rear water-head extending the entire width of the boiler, and relatively large, inclined water tubes interconnecting said front and rear water-heads, one or more upper water drums welded on to said lower unit, each of said upper water drums having fire tubes passing therethrough and communicating with the combustion chamber of said boiler, each of said drums being connected at its front and rear ends with said front and rear water-heads, and a baffle 10 extending rearwardly from the front water-head of said lower unit below said upper water drums.

5. A boiler comprising a lower unit adapted to be positioned on a prepared foundation and consisting of a front water-head extending the entire width of the boiler, a rear water-head extending the entire width of the boiler, and relatively large, inclined water tubes interconnecting said front and rear water-heads, and one or more upper water drums welded on to said lower unit, each of said upper water drums having fire tubes passing therethrough and communicating with the combustion chamber of the boiler, and each of said drums being also connected at its front and rear ends with said front and rear water-heads, and a smoke header communicating with the front ends of the fire tubes in said upper drums, 20 the rear ends of said fire tubes leading into a smoke stack.

6. A boiler comprising a lower unit adapted to be positioned on a prepared foundation and consisting of a front water-head extending the entire width of the boiler, a rear water-head extending the entire width of the boiler, and relatively large, inclined water tubes interconnecting said front and rear water-heads, and one or more upper water drums welded on to said lower unit, each of said upper water drums having fire tubes passing therethrough and communicating with the combustion chamber of the boiler, and each of said drums being also connected at its front and rear ends with said front and rear water-heads, a smoke header communicating with the front ends of the fire tubes in said upper water drums, a smoke stack communicating with the rear ends 30 of said fire tubes, and a baffle for preventing the escape of the products of combustion directly into said smoke stack.

HOWARD G. SMITH.
